MAX SOLASH, OF NEW YORK, N. Y.

ADJUSTABLE CAP.

Application filed June 21, 1924. Serial No. 721,470.

My invention relates to that class of caps or hats which are adjustable around the head to fit heads of widely different sizes and to compensate for shrinking or ill fitting.

Caps of this kind have been heretofore proposed with slits or openings in the lower edge of the cap fabric at each side of the visor, tabs extending from the rear portion 10 of the cap over the slits to the front of the cap and adjusting means for drawing the ends of the straps together. Stiffened tongues have also been proposed attached to the sides of the visor and projecting rearwardly between the lining and the cap fabric to guide and keep the lower edge of the cap in its varied adjustments.

But said slits or openings are objectionable in appearance and weaken the structure 20 of the cap.

My invention consists primarily in a peculiar construction of the pattern and fabric blank from which the cap is made and of the guiding tongues so that when the cap is put 25 together full allowance is made for the adjustment of the head band or portion without slitting or opening that portion of the cap and without causing any discomforts to the wearer, all substantially as hereinafter 30 described and claimed.

In order that my invention may be fully understood I shall first describe in detail the mode in which I at present carry my invention into practice and then particularly 35 define the invention in the claim.

Reference is to be had to the accompanying drawings forming part of this application in which the same parts are designated by like numbers in all the figures.

40 Figure 1 is a perspective view of an adjustable cap made in accordance with my invention.

Figure 2 is a plan of the pattern from which the body of the said cap is made, before stitching.

Figure 3 is an enlarged perspective view of the inside of the cap partly broken away showing the special formation of the adjustable portions thereof.

50 In the cap shown in the drawings, 9 is the fabric blank of cog-wheel pattern from which the fabric body 10 of the cap is made, the adjacent radial edges of the fabric seg-

ments 11, 12, 13 and 14 on each side being stitched together to form the fulled body 55 of the cap.

In making caps, these cog-wheel patterns and blanks are usually made in three sizes (1) large for the sizes from 7 1/4 to 7 5/8 inclusive, (2) medium for the most common 60 sizes 7 and 7 1/8, and (3) for the sizes below 7.

In my invention I avoid the lateral lower edge openings heretofore left or cut to permit the peripheral adjustment and provide 65 for stitching together the adjacent edges of the segments 12 and 13 on each side throughout to the bottom edge without using a pattern larger than the required size.

I accomplish these important results by 70 extending the lower portions of the segments of the pattern and fabric on each side of the visor forwardly so as to form triangular extensions 15 tapering from nothing at about the middle of the front edge of the segment 75 13 to a considerable width at the outer edge of the segment and its extension, as best shown in Figure 2.

Then when the adjacent edges of the segments 12 and 13 on each side are stitched 80 together to form the seams 16 a downward bell or flare will be formed in the lower portion of the cap at each side of the visor.

Around the rear of the cap between the lining 17 and the cap fabric is placed the 85 usual inside rear stiffening strip 18, which is stitched to the lower edge of the cap fabric and terminates at its forward ends a short distance from the respective ends of the visor. The front stiffening strip 19 is extended upwardly from the stiffening of the visor and terminates at its rear ends at about the ends of the visor so that spaces are left between the respective ends of the rear and front stiffening strips, which are 90 95 covered by the soft fabric extensions 15 of the segments 13.

To the rear ends of the front stiffening strip 19 are stitched, or may be formed integrally therewith, rearwardly extending 100 stiffened tongues 20 preferably of fabric, sliding lengthwise in loops or keepers 21 also preferably of fabric and attached to the inside of the cap fabric inside the lining. To loosen or tighten the adjustable head band 105 thus formed, I in the present example of

my invention employ forwardly extending tabs 22 stitched or attached on each side to the lower fabric of the cap at the seams 16 and extending forwardly around the front 5 of the cap where they are joined together by an adjustable strap 23, which can be shortened or lengthened at will by a buckle 24.

With this construction and arrangement when the adjustable strap 23 is shortened 10 to tighten the head band of the cap, the triangular soft fabric extensions 15 are gathered or folded between the tongues 20 on the inside and the tabs 22 on the outside as the respective separated ends of the front 15 and rear stiffening strips 18 and 19 are brought nearer together. Thus the folds of the soft extensions 15 are kept flat and do not cause any discomfort to the wearer while the undesirable slits or openings in 20 the fabric heretofore proposed are avoided.

It must be kept in mind that the slits or openings have been heretofore left to avoid using a larger pattern and more cloth than usual for the size, and that my triangular 25 soft extensions or projections 15 from the front edges of the pattern segments 13, also render unnecessary the use of an oversize

pattern, but without leaving the sides of the cap open.

I claim as my invention:

A cap, the body of which is formed with radial segments, opposite ones of which are provided with substantially triangular extensions, the adjacent edges of the segments and extensions being attached together, tabs 30 attached to the outside of the cap body and covering the said extensions, means for drawing said tabs together to form folds in the extensions and take up any excess fullness in the cap body, two stiffening strips 35 attached to the inside of the cap body along the periphery of the head opening, one of said strips being located in front of the extensions, and the other being located at the rear of said extensions, keepers on the rear stiffening strip, and stiff tongues stitched to the ends of the front stiffening strip 40 covering the extensions and slidably in the said keepers to press the folds against said tabs and keep the stiffening strips aligned to 45 any adjustment of the cap body.

In testimony whereof I affix my signature.

MAX SOLASH.
